UNITED STATES PATENT OFFICE.

FRANK M. COE, OF NEW YORK, N. Y.

WHEEL GRIP.

Application filed June 20, 1922. Serial No. 569,685.

To all whom it may concern:

Be it known that I, FRANK M. COE, a citizen of the United States, and residing at New York city, in the county of New York 5 and State of New York, have invented a certain new and useful Improvement in Wheel Grips, of which the following is a specification.

The object of my invention is to provide 10 vehicles, particularly tractors, with wheel grips, constructed and mounted so as to insure against slipping of the wheels, regardless of the character of the ground in which the tractor is working.

15 A further object is to provide means for quickly attaching or detaching the wheel grips, said means also functioning to securely seat and hold the grips in place.

20 A further object is to provide a securing means adapted to engage and hold in place a plurality of the grips, by a single operation of tightening and clamping.

25 Other and particular objects will be obvious, to a person skilled in the art, by a careful reading of the specification and reference to the drawings.

30 My invention consists of certain details of construction hereinafter set forth, pointed out in my claims and illustrated in the accompanying drawings in which—

Fig. 1 is a side elevation of my improved wheel equipped with my improved lugs.

35 Fig. 2 is an end elevation of the same partly broken away to show the interior construction.

Fig. 3 is a side elevation of the latticed form of wheel.

Fig. 4 is an end elevation of the wheel as shown in Fig. 3.

40 Figs. 5, 6 and 7 are enlarged detail views of the grips, Figure 6 showing the formation of one of the grips used for the center of the periphery of the wheel.

Fig. 8 is a sectional view taken on the 45 line 8—8 in Fig. 6.

Fig. 9 is a detail view of the securing ring.

Referring to the accompanying drawing the reference numeral 10 is used to indicate one of the drive wheels of a tractor, orificed 50 at 11 in its periphery as shown. These orifices are uniform and evenly spaced and arranged preferably near the sides of the periphery, and are adapted to receive lugs, or grips, 12 which are formed with a depending shank 13 on which is a hook 14, a shoulder 15 being provided to form a mem-

ber to seat within the orifice, the base of the lug being seated against the periphery of the wheel. Obviously the lugs, or grips, taper toward their outer ends to provide 60 for them biting into the ground as the wheel is rotated.

As before stated each of these grips have a hook formed at the lower end of their depending shanks and the base of the grips 65 rests flush against the outer surface of the wheel, the depending member of the grip formed by the shoulder, being seated in the orifice, the shank with its hook projecting downwardly. A metal band (preferably 70 round in conformation) 16, screw threaded on both of its ends, circles the lugs and is seated in a hook on each lug, the ends of the rod engaging screw threads in the two ends of a joining member 17.

75 When the grips, or lugs, have been seated in their respective orifices the encircling (or tightening) band is seated in the hooks (as clearly shown in Fig. 1) and the joining member 17 rotated. This draws the ends 80 of the rod 16 together, thus obviously drawing the lugs to a firm position in their respective seats.

In practical demonstrations I have been able to attach or detach, the grips to the 85 wheels in an incredibly short space of time.

A large portion of traction wheels are of what is known as the skeleton, or latticed type which are formed of annular rims spaced apart and held in relative position 90 by spanning, or bridging, members, and it is for such wheels that my improved grips are particularly designed. As will be noted in the drawings 1 provide channels 18 in the base of my grips, to receive the lattice members forming the wheel and in this manner the grip is firmly seated in position and held in place by the securing means. The grips thus formed may be attached to the center or sides of a latticed wheel.

100 Many minor changes may be made in the technical construction of the grips without in any manner effecting their functioning or the functioning of the securing band, and I do not therefore desire to be understood as 105 limiting the scope of my protection except as outlined in the accompanying claims.

Having thus described my invention what I claim and desire to secure by Letters Patent of the United States is:

110 1. Grips for tractor wheels comprising lugs channelled to fit over the latticed rim

members of a wheel, said grips having depending shafts terminating in a hook; a securing band adapted to be seated in the said hooks with means for tightening and loosening said band, substantially as shown and described.

2. A plurality of gripping devices for tractor wheels each comprising a lug channeled to engage and overlap portions of the

latticed members forming the rim of the 10 wheels, said lugs being designed to collectively function and certain groups of them being held in place by common securing means.

In testimony whereof, I have signed the 15 foregoing specification.

FRANK M. COE.
